SLIDING PROTECTING SHADE FOR STORE SHELVES

Rolland F. Burdo, Toledo, Ohio

Application May 6, 1936, Serial No. 78,253

3 Claims. (Cl. 312—190)

This invention relates to store furniture and more particularly to a sliding shade for housing and protecting all kinds of goods on store shelves or in display cases, cabinets and the like.

5 One object of the invention is to provide a protecting shade of simple and inexpensive construction adapted to be positioned on a store shelf or within a display cabinet and which will effectually protect the goods on display from dust and dirt, 10 while, at the same time, permitting clear visibility thereof and ready access thereto at all times.

Another object of the invention is to provide 15 a protecting shade comprising coacting tracks between which is slidably mounted a flexible transparent shield or curtain movable manually to different positions of vertical adjustment with respect to the store shelf or cabinet and which may be held in any desired position of adjustment without the employment of catches, springs, 20 or other operating devices.

A further object of the invention is to provide 25 a novel form of guard which performs the dual function of preventing inward movement or buckling of the guide tracks and as a means for preventing the deposit of dust and dirt on the shelf or on the goods displayed thereon when the flexible curtain is in lowered position.

A still further object of the invention is generally 30 to improve this class of devices so as to increase their utility, durability and efficiency.

In the accompanying drawings forming a part 35 of this specification and in which similar numerals of reference indicate corresponding parts 25 in all the figures of the drawings.

Figure 1 is a perspective view of a display case or cabinet provided with a sliding protecting shade constructed in accordance with the present invention.

40 Figure 2 is a transverse sectional view, taken on the line 2—2 of Figure 1.

Figure 3 is an enlarged detail sectional view 45 showing the guard strip back of the track flanges and the curvature of the curtain reinforcing strips.

Figure 4 is a perspective view of the guide tracks and dust guard removed, the several parts being shown in a position ready to be assembled.

50 Figure 5 is a front elevation of the flexible shield or curtain.

Figure 6 is a vertical sectional view showing the device applied to a store shelf.

The improved protecting shade or curtain forming the subject-matter of the present invention 55 may be used in connection with cabinets or cases

for displaying goods and the like or applied to store shelving and in Figure 1 of the drawings is shown in connection with a display cabinet of conventional construction, in which 5 designates the top, 6 the side walls, 7 the bottom or shelf, 5 and 8 the supporting legs.

The device comprises spaced guide tracks 9 and 10 adapted to be positioned against the end walls of the cabinet and extend transversely beneath the top thereof and vertically at the front of the 10 cabinet. The guide tracks are preferably stamped or otherwise formed from sheet metal and are substantially U-shape in cross section with the open sides of the tracks facing each other, as best shown in Figure 4 of the drawings. Each 15 guide track is preferably formed in two sections 11 and 12 having laterally extending flanges 13 formed at the junction of the curved portions thereof and provided with registering openings 14 for the reception of a bolt or similar fastening 20 device 15 whereby the sections may be rigidly secured together. The lower end of the track section 11 is formed with an angularly disposed attaching foot 16 adapted to be secured to the adjacent surface of the supporting shelf 7, while 25 the track section 12 is provided with a similar depending attaching foot 17 which is bolted or otherwise rigidly secured to the rear wall of the cabinet, as best shown in Figure 2 of the drawings.

Slidably mounted between the guide tracks 9 30 and 10 is a vertically movable shield or curtain 18 preferably formed of clear transparent number twenty "Plastacele", although any other transparent flexible material may be used if desired. The upper and lower edges of the curtain 18 are reinforced by metallic strips 19 which preferably project slightly beyond the adjacent edges of the curtain and fit within the open sides of the track and serve to guide the curtain when moved to either raised or lowered position. The 40 lower reinforcing strip is provided with a finger-piece or loop 20 so that the curtain may be readily grasped to facilitate operating the same.

In order to prevent the entrance of dust and dirt into the interior of the cabinet when the 45 curtain 18 is in lowered position, I provide a guard 21 preferably in the form of a flat metallic strip, the opposite ends of which are slotted, at 22, and adapted to fit over the adjacent securing bolts 15. The slotted ends of the guard 21 may 50 either be interposed between the flanges 13 as shown in Figure 2 or bear against the back of said flanges as shown in Figure 3, the bolts 15 in each case when tightened serving to hold the guard 21 in a fixed position. This guard 21 acts 55

as a connecting brace for the tracks and serves to prevent inward movement or buckling thereof, and as the upper longitudinal edge of the guard 21 rests snugly against the lower surface of the top 5 of the cabinet, said guard acts as a dust-proof barrier to prevent dirt and other foreign particles from entering at the top of the cabinet and damaging the goods displayed therein when the curtain is lowered.

10 As the upper and lower reinforcing strips of the curtain are curved transversely and frictionally engage the walls of the guide tracks, said curtain can be securely held in any position of adjustment without the employment of catches, 15 springs and the like.

In operation, if it is desired to obtain access to goods or other commodities displayed within the cabinet, it is merely necessary to grasp the handle 20 and exert a slight upward pressure on the lower end of the curtain 18 which will cause the upper end of the curtain to travel in the horizontal portions of the guide tracks 9 and 10 immediately beneath the top of the cabinet so that access may be readily had to the goods within the cabinet. When the curtain is moved to lowered position, the merchandise within the cabinet will be clearly visible through said curtain, while, at the same time, said merchandise will be thoroughly protected from dust, dirt and other foreign matter and this exclusion of dust from the interior of the cabinet is further enhanced by the provision of the guard 21 which, as previously stated, prevents the possibility of dust entering at the top of the cabinet when the curtain is lowered.

If the cabinet is provided with two or more display shelves, individual tracks and individual curtains may be provided for each shelf, if desired.

40 In Figure 6 of the drawings, the sliding protecting shade is shown applied to a conventional form of store shelving 23 for the purpose of protecting goods displayed on said shelving. In store shelving the space immediately above each shelf is often of greater height than the width of the shelf and when this is the case, I provide auxiliary tracks 24 which may be fastened to the track sections 12 by flanges 25 through which extend bolts or similar fastening devices 26. The auxiliary track 24 serves to receive and guide the adjacent end of the curtain in parallel relation to the rear wall of the store shelving when the curtain is moved to open position, as will be readily understood.

55 A device constructed in accordance with the present invention will not only effectively house and protect goods supported on a store shelf or within a display cabinet, but will permit clear visibility of the goods at all times without the employment of glass or other frangible material, as at present.

It will, of course, be understood that the guide tracks may be made in different sizes and shapes to adapt them to particular requirements and that various details in the construction of the device may be changed or varied at will without departing from the spirit of the invention.

Having thus described the invention, what is claimed as new is:

1. In combination with a cabinet having a body open at its front and including a display shelf and a flexible curtain for closing the open front of the body; guide tracks for the curtain formed separate from the body and rising from opposite ends of said shelf against side walls of the body at the open front of the body and having upper portions extending rearwardly against the top of the body, ends of the tracks being secured against the shelf and the back of the body, and a strip carried by and connecting the guide tracks at the upper end of the open front of the body and serving as a brace for the track, said strip bearing against the top of the body over the curtain and constituting a guard for preventing the entrance of dust to the interior of the body when the curtain is in the lowered position.

2. In combination with a display cabinet having a body open at its front and including a display shelf and a flexible curtain for closing the open front of the body, guide tracks for the curtain disposed at opposite ends of the body and each comprising a vertical section and an upper horizontal section, said sections having adjoining ends provided with confronting upwardly extending tongues, securing bolts extending through said tongues, and a strip carried solely by said tracks and forming a brace between the tracks and having its opposite ends interposed between said tongues of the sections and slotted to receive the securing bolts, said strip constituting a guard extending across the top of the open front of the body and adapted to block space between the top wall of the body and said curtain for preventing the entrance of dust to the interior of the body when the curtain is in a lowered position.

3. In combination with a display cabinet having a body open at its front and including a display shelf and a flexible curtain for closing the open front of the body, guide tracks for the curtain formed of channel metal substantially U-shape in cross section, said tracks being disposed at opposite ends of the cabinet along the front edges and upper edges of the end walls of the body and having their open sides facing each other, said guide tracks each comprising a vertical section and an upper horizontal section formed at their adjoining ends with upwardly extending diagonally disposed tongues, bolts extending through said tongues, a laterally inclined bar of flat metal extending across the top of the open front of the body and carried solely by the tracks and secured at its ends by said bolts and forming a brace between the guide tracks at the adjoining ends of the sections thereof, said bar constituting a dust barrier between the curtain and the forward edge portion of the top wall of the body, the tracks and said bar being formed independent of the body and the track sections being provided with tongues at their outer terminals adapted to receive fasteners for securing the tracks in place.

ROLLAND F. BURDO.
